UNITED STATES PATENT OFFICE.

ALFRED H. DYSON, OF MONTCLAIR, NEW JERSEY, ASSIGNOR TO WESTERN ELECTRIC COMPANY, OF NEW YORK, N. Y., A CORPORATION OF ILLINOIS.

TELEPHONE SYSTEM.

1,163,899.

Specification of Letters Patent.

Patented Dec. 14, 1915.

Application filed March 31, 1914. Serial No. 828,586.

To all whom it may concern:

Be it known that I, ALFRED HARTWELL DYSON, a citizen of the United States, residing at Montclair, in the county of Essex 5 and State of New Jersey, have invented a certain new and useful Improvement in Telephone Systems, of which the following is a full, clear, concise, and exact description.

10 This invention relates to automatic telephone systems.

The invention is applied to a system in which automatic connecting switches located at a central office are controlled over two line 15 wires leading to a subscriber's station without the aid of a third conductor.

The object of this invention is to provide means for variously controlling the switches of the system over these two line conductors.

20 The particular classes of control here provided for are the movement of the contacts of a switch to a desired position, the maintenance of the switch in this desired position during the control of other switches 25 and the return of the switch to its normal position. The means by which the foregoing controls are accomplished is a pair of ratchet wheels, which, when actuated through the agency of electromagnets, function to alter circuit conditions after the lapse 30 of a predetermined interval. This interval may be varied by slight changes in the design of said ratchet wheels as will hereafter be fully described.

5 The invention is illustrated in the accompanying drawings in which—

Figure 1 is a front view of the mechanism for obtaining the desired time interval in its normal position, and Fig. 2 is a circuit diagram showing the portion of a telephone system in which this mechanism is used.

In Fig. 1 electromagnets 15 and 24 are mounted by means of brackets 81, 82. Upon brackets 81, 81 are pivotally mounted armatures 12 and 13 which carry cams 70 and 71, respectively. Plates 75, 75 have mounted thereon by means of a pin, springs 73, 74. Said springs 73, 74 have a slot cut in one end through which cams 70 and 71 extend and are held in engagement with said slot by means of springs 86, 86. Upon the forward stroke of armatures 12 and 13 the cams 70 and 71 are pulled through the slot until they are on the opposite side of springs 73, 74 to that which they are normally held. Said

35 cams 70 and 71 are not pulled through the slots of said springs 73 and 74 until the completion of the stroke of armatures 12 and 13 when actuated in either a forward or backward direction. The tension of the outside 60 springs of contacts 16 and 25 is in a direction away from electromagnets 15 and 24, which causes said springs to recede from their normal contact and to follow springs 73, 74 until springs 73, 74 come to rest against 65 stop pins 83, 83. When these contacts are opened, the circuit for electromagnets 15 and 24 is broken, thus allowing springs 87, 87 to restore armatures 12 and 13 to normal position, which again close contacts 16 and 25. 70 It follows that the cams 70 and 71, together with springs of contacts 16 and 25 and springs 73, 74 constitute an interrupter for electromagnets 15 and 24.

75 Pawls 10 and 11 are pivotally mounted near the extreme end of armatures 12 and 13 and are held in position by springs 9, 9 so as to engage the teeth of ratchet wheels 1 and 2, when said armatures 12 and 13 are attracted upon the energization of electromagnets 15 and 24. The movement of pawls 10 and 11 is limited by stop pins 6, 6 and 7, 7.

80 Ratchet wheels 1 and 2 are mounted in operative relation with pawls 11 and 12 by means of pivots. Said wheels 1 and 2 are restored by springs 5, 5. In case ratchet wheel 1 has been restored by spring 5, pawl 4 engages one of the teeth 85 of ratchet wheel 2. When ratchet wheel 90 1 is in this position, pawl 11 of armature 13, upon the energization of electromagnet 15, engages one of the teeth of said ratchet wheel 1, pawl 4 is moved out of engagement with the teeth of wheel 2 by means 95 of cam 85 formed on the periphery of said ratchet wheel 1, and is held in that position until said ratchet wheel 1 is again restored by spring 5. The rotation of ratchet wheel 100 1 step by step in a counter-clockwise direction, is obtained by means of the interrupter composed of contact 16, spring 73 and cam 71, which causes the energization and de-energization of electromagnet 15. The rotation of said ratchet wheel 1 will continue 105 until the cam 84 passes beyond and out of engagement with spring of contact 19, allowing said contact 19 to open. The opening of contact 19 breaks the circuit of electromagnet 15, consequently preventing any further 110

rotation of ratchet wheel 1. The interval of time during which contact 19 remains closed, after ratchet wheel 1 commences to rotate, is predetermined and may be varied by changing the size of cam 84. It may be stated here, that, at the completion of a call when the subscriber hangs up the receiver, ratchet wheel 1 is left in the position shown in Fig. 1, contact 19 being normally open. 10 This operation will be more fully described hereafter.

Ratchet wheel 2 is rotated step by step in a clockwise direction upon the energization and deenergization of electromagnet 24, in a manner similar to the rotation of ratchet wheel 1, as described above. When said ratchet wheel 2 is rotated the first step, cam 90 causes pawl 3 to become disengaged from the teeth of ratchet wheel 1, which allows it to return to be restored by means of spring 5. 15 As ratchet wheel 2 continues to rotate, cam 91 passes beyond and out of engagement with the spring of contact 22, which permits said spring to engage with its mate, thus closing contact 22. Pin 8, by engaging with the spring of contact 18, opens said contact. Said pin 8 is so positioned that contact 22 is closed before contact spring 18 is opened. The time required for the closing and opening of said contacts is predetermined and may be varied by changing the size of cam 91 and position of pin 8.

The parts illustrated in Fig. 1 which enter into the electrical circuits of the system are represented in Fig. 2 by numerals 15, 16, 18, 19, 22, 24 and 25. In this figure the calling subscriber's station 30 is provided with the usual transmitter and receiver and with a controlling device having contacts 31 30 arranged to open the circuit of the line conductors 32 and 33 in the transmission of a signal. This line is connected through suitable switch contacts with the conductors of a selector switch circuit wherein the line conductor 32 extends through one winding of relay 34 to the live pole of central battery 35, and line conductor 33 extends through another winding of relay 34 to the ground pole of said battery. The preliminary closure of the line at the subscriber's station 40 by the removal of the subscriber's receiver from its hook, energizes relay 34, causing the closure of its front contacts 36 and the consequent energization of relay 37. At the same time electromagnet 24 is energized by the following circuit: ground, front contacts 36 of relay 34, contacts 18, 25, coil of electromagnet 24, to battery. This circuit is interrupted by the opening and closing of contact 25 under the influence of armature 12 in a manner as previously described. The energization and deenergization of electromagnet 24 rotates ratchet wheel 2 out of normal position, thus causing the disengagement of pawl 3 from the teeth of ratchet

wheel 1, which allows said ratchet wheel to be restored by means of spring 5. This establishes a locking circuit for relay 37 through its front contact 38 and contact 19. Electromagnet 24, through the interruption 70 of its circuit, continues to rotate ratchet wheel 2 until battery is removed by the opening of contact 18 by means of pin 8.

A series of interruptions is now produced by means of the circuit breaker 31 at the subscriber's station 30, the number of interruptions depending upon the number of the desired subscriber's telephone, and being in all events equal in number to one of the digits of the desired subscriber's number. 80 At the first interruption, relay 34 releases its armatures. The first release completes a circuit through back contacts 40 of relay 34, front contacts 43 of relay 37, contact 16 and the coil of electromagnet 15, this circuit 85 including the battery 35. The periodic closures of this circuit and consequent energizations of electromagnet 15, causes ratchet wheel 1 to be rotated momentarily, thus causing pawl 4 to be disengaged from the 90 teeth of ratchet wheel 2, which permits said ratchet wheel 2 to return to normal position under the influence of spring 5. While the interruptions are being sent over the line, electromagnets 15 and 24 are energized and 95 deenergized in rapid succession, the control of each by the other being such that neither ratchet may be rotated more than one or two steps before being released by the operation of the other. This oscillation continues 100 until the interruptions cease, whereupon ratchet wheel 2 is rotated off normal.

At each deenergization of relay 34, the back contacts 42 of that relay complete a circuit through front contacts 41 of relay 37, conductor 44, contacts 45 and the coil of primary stepping magnet 46 to battery. Current in this path energizes the stepping magnet 46 once for each time that the circuit is interrupted at subscriber's station 110 30. The switch controlled in its primary movement by stepping magnet 46 is of a type in which each energization and deenergization of the primary magnet 46 moves a set of contact wipers in front of a 115 group or row of contacts; thus one energization of the primary magnet 46 places the wipers in front of one group of the contacts, two energizations and deenergizations in front of another and so on, the number of 120 groups usually being ten.

At the completion of the first series of interruptions, the circuit through electromagnet 24 is closed for a sufficient interval of time, which is predetermined and may be varied as hereinbefore described, to allow ratchet wheel 2 to be rotated until contact 22 is closed and contact 18 is opened. The opening of contact 18 prevents any further rotation of said ratchet wheel 2 by breaking 125 130

the circuit of electromagnet 24. A circuit is now completed through the impedance coil 39, contact 22, conductor 47, contacts 49 of the secondary off normal set of springs, through contacts 48 of the primary off normal set of springs, which are arranged to close upon the first energization of magnet 46, and the coil of relay 50 to battery, thus actuating the relay 50. The actuation of relay 50 completes a circuit through its front contacts 51, interrupter contacts 52 and secondary stepping magnet 53 to battery. The magnet 53 is adapted to move the contact wipers over the contacts of the group which has been picked out by the previous actuation of magnet 46, the circuit 53 being made and broken by its own contacts 52 so long as the relay 50 remains in its actuated condition. Upon the first actuation of secondary magnet 53, the wipers 54 were moved into contact with the first of the series of contacts in the particular group which had been picked out by directive actuation of primary magnet 46. These contacts are connected with trunk lines extending to other switches and as will be hereafter explained, the contacts connecting with busy trunk lines will have a guarding potential thereon to indicate the busy condition. Considering that the first few contacts to be reached by the private wiper 54 are thus guarded by a ground potential, a circuit is completed through conductor 55, front contacts 56 of relay 37, front contacts 57 and coil of relay 50 to battery. Current in this part maintains the actuation of relay 50, which maintains the circuit through the secondary stepping magnet 53 until the private wiper 54 arrives upon a non-grounded trunk contact, whereupon the circuit in the path just described is interrupted and the relay 50 resumes its normal position, opening the circuit of the secondary stepping magnet 53 and closing its own back contacts 58, thus putting ground potential upon wiper 54 and the contact of the trunk just selected to guard this trunk against its selection by other switches. It may be stated here that the secondary off normal contacts 45 and 49 were interrupted upon the first actuation of secondary stepping magnet 53. The next series of interruptions which are made by the controller 31 at the subscriber's station in designating the second digit of the desired number similarly deenergizes the relay 34 but this time, instead of controlling the circuit of the selector switch shown in the drawings, the circuit of the next switch in the series will be controlled. Primary magnet 46 and secondary magnet 53 are not actuated because their respective circuits are broken through the opening of secondary off normal contacts 45 and 49 as described above. As before, the electromagnet 15 will be energized by the first deenergization of relay 34, which restores ratchet wheel 2 to normal position, and at each energization and deenergization of relay 34 ratchet wheels 1 and 2 will oscillate as herein previously described. At each deenergization of relay 34 a circuit will be completed through the back contacts 42, front contacts 41 of relay 37, conductor 44, back contacts 60 of relay 50, wiper 61, conductor 62 and a magnet of the next switch in the series. At the lapse of a predetermined interval as before described, contact 22 is closed, which completes a circuit through impedance 39, contact 22, conductor 47, back contacts 63 of relay 50, wiper 64, conductor 65 and a relay or electromagnet of the next switch in the series to be controlled. This succeeding switch may be of the type disclosed in the patent to me, No. 975,608, of November 15, 1910.

In order to return the switch to its normal position, the circuit at the subscriber's station is opened by replacing receiver upon the hook. Relay 34 then releases its armatures which fall away, closing the back contacts 40 and 42. Electromagnet 15 is, therefore, actuated by the closing of the following circuit: ground, back contact 40 of relay 34, front contacts 43 of relay 37, contact 16 and the coil of electromagnet 15 to battery. This causes ratchet wheel 1 to rotate, restoring ratchet wheel 2 to normal, and the consequent closing of contact 18, and opening of contact 22, as before described. The rotating of ratchet wheel 1, after the lapse of a predetermined time, opens contact 19. This breaks the locking circuit for relay 37 and permits that relay to return to normal, closing its back contacts 69. A circuit is thus established through back contacts 42 of relay 34, back contacts 69 of relay 37, primary off normal contacts 48 and coil of relay 50 to battery. The actuation of relay 50 again brings the secondary stepping magnet 53 into circuit which, through its pawl, continues the movement of wipers 54, 61 and 64 over the contacts until the switch has been moved to its extreme secondary position beyond the last contact of the group. At this point the primary retaining pawl is tripped, permitting the switch to return to its normal position so far as its primary movement is concerned. At the end of this primary movement, the secondary retaining pawl is tripped, permitting the switch to return to its normal position so far as the secondary movement is concerned. The interruption of contacts 56 of relay 37, removed the guard potential 1 from private wiper 54, and caused the release of the next succeeding switch in the series. All of the apparatus is then returned to its normal position and is in readiness for a second call, the ratchet wheels 1 and 2 assuming the position shown in Fig. 1.

Ratchet wheel 1 remains in this position until restored by the spring 5 when ratchet wheel 2 is rotated upon the removal of the receiver at subscriber's station 30, when initiating another call.

5 It is to be understood that the apparatus of Fig. 1 may be applied to many other types of system than that shown in Fig. 2, and that modifications may be made in 10 the apparatus itself without departing from the spirit or scope of this invention.

What is claimed is:

1. In a telephone system, the combination 15 with a telephone line, of an interrupter mechanism at the subscriber's station of said line, a switch at the central office, a primary controlling magnet, a secondary controlling magnet, a controlling relay for said magnets under the control of said substation interrupter, and a circuit changing device comprising two electromagnetic interrupters and a ratchet mechanism actuated thereby, said ratchet mechanism functioning to alter circuit conditions after the last deenergization of said controlling relay to switch 20 the current controlled by said relay from one of said controlling magnets to the other. 25

2. In a telephone system, the combination 30 with a telephone line, of an interrupter mechanism at the subscriber's substation of said line, a switch at the central office, a controlling relay for said switch under the control of said substation interrupter, two electromagnetic interrupters, a pair of 35 ratchet wheels actuated by said interrupters and so positioned that the rotation of one releases the other if the latter is in an off-normal position, one or the other of said ratchet wheels being always responsive to 40 said controlling relay.

3. In a telephone system, the combination 45 with a telephone line, of an interrupter mechanism at the subscriber's substation of said line, a switch at the central office, a controlling relay for said switch, said relay being energized and deenergized by the interruption produced at the subscriber's substation, two step by step circuit changing interrupters, one of said interrupters being 50 responsive to said controlling relay when said relay is energized, and the other being responsive when said relay is deenergized.

4. In a telephone system, an impulse transmitter, a relay controlled thereby, a 55 pair of electromagnetic circuit controlling devices mechanically operating upon one another whereby each when operated releases the other, an operating circuit for one of said electromagnetic devices closed by the 60 actuation of said relay, and an operating circuit for the other electromagnetic device closed by deenergization of said relay.

5. In an automatic telephone system, the combination with a selector switch, of a primary controlling magnet and a secondary

controlling magnet for said switch, a relay for controlling said primary magnet, a circuit changing device comprising two electromagnetic interrupters and a ratchet mechanism controlled thereby, said ratchet mechanism functioning to bring the secondary magnet into action at a predetermined time after the last action of the primary magnet. 70

6. In a telephone system, the combination 75 with a selector switch, a set of movable contacts for said switch and a plurality of sets of stationary contacts, an electromagnet for causing the step-by-step movement of the movable contacts to various sets of stationary contacts, a relay for controlling said electromagnet, and a circuit changer including two electromagnetic interrupters having associated therewith a ratchet mechanism also controlled by said relay and adapted to remove said electromagnet from the control 80 of said relay at a predetermined time after the last control of said magnet by said relay.

7. In an automatic telephone system, the combination with a selector switch, of a primary controlling magnet and a releasing 90 magnet for said switch, a relay initially causing the completion of the circuit of the primary magnet each time it releases its armatures, and a switching device including two electromagnetic interrupters, a ratchet mechanism associated therewith, said switching device acting after a predetermined time from the last release of the armatures of said relay to place the releasing magnet under the control of said relay so as to return the selector switch to its normal position if said relay is at that time in its unactuated condition. 100

8. In an automatic telephone system the combination with a plurality of central office 105 circuits to be controlled by a plurality of series of controlling impulses, a pair of mechanically connected electrically actuated time controlled switching devices operated between each series of impulses to change 110 the circuit to be controlled.

9. In combination with a circuit changing device, two electromagnetic interrupters, a pair of ratchet wheels, a cam operated by each ratchet wheel, contact springs controlled by said cams and circuits therethrough opened and closed at a predetermined time after said ratchet wheels are rotated by means of said electromagnetic interrupters. 115

10. In combination with a circuit changing device, two electromagnetic interrupters, a pair of ratchet wheels so positioned that the rotation of one releases the other if the latter is in an off-normal position, cams operated by said ratchet wheels, contact springs operated by said cams which make and break contact at a predetermined time after said ratchet wheels are rotated by means of said electromagnetic interrupters. 120

11. The combination with a circuit changing device, two electromagnetic interrupters, a pair of ratchet wheels actuated thereby, contact springs controlled by said ratchet wheels and means for opening the circuit therethrough of one of said interrupters at the lapse of a predetermined time to prevent further rotation of the ratchet wheel controlled by said interrupter.
12. The combination with a circuit changing device, two electromagnetic interrupters, a pair of ratchet wheels actuated thereby, contact springs controlled by said ratchet

wheels and means carried by one of said ratchet wheels for opening the circuit therethrough of one of said interrupters at the lapse of a predetermined time to prevent further rotation of the ratchet wheel controlled by said interrupter. 15

In witness whereof, I hereunto subscribe 20
my name this 28 day of March A. D., 1914.

ALFRED H. DYSON.
